UNITED STATES PATENT OFFICE

105,505

DESIGN FOR A BULLETIN BOARD SIGN OR THE LIKE

Joe B. Rives, Maramec, Okla.

Application May 18, 1937, Serial No. 69,400

Term of patent 14 years

To all whom it may concern:

Be it known that I, Joe B. Rives, a citizen of the United States, residing at Maramec, in the county of Pawnee and State of Oklahoma, have invented a new, original, and ornamental Design for a Bulletin Board Sign or the like, of which the following is a specification, reference being had to the accompanying drawing, forming part thereof, and in which

Fig. 1 is a front view,
Fig. 2 is an edge view, and
Fig. 3 is a rear view of a bulletin board sign showing my new design.

I claim:
The ornamental design for a bulletin board sign or the like as shown.

JOE B. RIVES.
